DESIGN FOR AN ASHTRAY

John Gano Seder, Fort Collins, Colo.

Application July 29, 1937, Serial No. 70,717

Term of patent 7 years

To all whom it may concern:

Be it known, that I, John Gano Seder, a citizen of the United States, residing at Fort Collins, in the county of Larimer and State of Colorado, have invented a new, original, and ornamental Design for Ashtrays, of which the following is a specification, reference being had to the accompanying drawing, forming part thereof, in which

The characteristic feature of the design resides in the columnar match box and match book support.

I claim:

The ornamental design for an ashtray as shown and described.

JOHN GANO SEDER.
